UNITED STATES PATENT OFFICE.

JOHN LAYTON GUERRANT, OF SEDALIA, MISSOURI.

FREIGHT-CAR DOOR.

1,260,374.

Specification of Letters Patent. Patented Mar. 26, 1918.

Application filed April 25, 1916. Serial No. 83,459.

To all whom it may concern:

Be it known that I, JOHN L. GUERRANT, a citizen of the United States, residing at Sedalia, in the county of Pettis and State of Missouri, have invented a new and useful Freight-Car Door, of which the following is a specification.

The present invention appertains to grain car doors, and aims to provide a novel and improved door structure adapted especially for grain cars, although useful upon other freight cars and elsewhere as well.

Generally considered, the invention embodies in connection with the door frame of a car body, or the like, inner and outer doors which when closed provide a grain tight closure which will exclude the elements, which will withstand the pressure and jars incident to the jolting or wedging action of the grain or merchandise thereagainst, and which cannot be opened by a person who has secreted himself in the car for purpose of throwing out merchandise while the same is in transit.

It is the object of the invention to provide a closure of the nature indicated which will be an all around protector of merchandise, preventing the injury thereof by dust, dirt, rain, sleet, and the like, and also providing a perfect barrier against theft.

Another object of the invention is the provision of novel means for mounting the inner door whereby it can be moved outwardly upon the outer side of the door frame, so that it can be moved to one side of the door way.

The invention also includes novel means for fastening the inner door in closed position, whereby it will be snugly and firmly held in place.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawings, wherein:

Figure 1 is an outside view of the door structure showing the outer door moved to one side to expose the inner door.

Fig. 2 is a horizontal section taken on the line 2—2 of Fig. 1.

Fig. 3 is a vertical section taken on the line 3—3 of Fig. 1.

Fig. 4 is an enlarged sectional detail showing the means for hanging the two doors, the doors being in closed position.

Fig. 5 is a view similar to Fig. 4 showing the outer door moved out of the way and the inner door moved outwardly in order that it can be moved away from the door way.

Fig. 6 is an enlarged sectional detail taken on the line 6—6 of Fig. 2.

The door frame includes a sill 1, posts or jambs 2 and a lintel 3, and an outer storm door 4 is movable slidably along the exterior 70 of the car body, as usual, in order that it can be readily moved across and away from the door way or opening. This outer door 4 is hung from a longitudinal horizontal track 5, constituting a housing, having the spaced 75 trough-portions 6 in which rollers 7 are mounted for rotation and which support the T-head 8 of a hanger 9 which extends downwardly between the portions 6 and which has its lower edge secured in any suitable 80 manner to the upper edge of the door 4. The T-head 8 can travel easily upon the rollers 8 to permit the door 4 to be moved easily toward or away from the door way. The track 5 extends over the door way and away 85 from the same toward one side thereof.

In conjunction with the outer door 4, there is used an inner door 10, preferably constructed of sheet metal, although it can be constructed of wood or other suitable material, and this door 10 is of a size to fit snugly within the door way or within the door frame. Attached to the outer surface of the door 10 are transverse or horizontal reinforcing members 11, and attached to the 95 edges of the door 10 are vertical reinforcing members 12 of channel iron or other suitable stock.

In order to mount this door 10 for movement into and out of the door frame, and for longitudinal sliding movement upon the exterior of the car body, a horizontal member 13 of angle iron or other suitable stock is attached to the outer surface of the door 10 adjacent its upper end, and outstanding 100 slotted bars or other members 14 are attached to the member 13 and door 10 and project outwardly from the upper end of the door. Said slotted members 14 are 105 slidable upon pins or rollers 15 carried by 110 the forked or bifurcated hangers 16 which are provided at their upper ends with T-

heads 17, there being any suitable number of members 14 and hangers 16. A secondary or supplemental track 18, similar to the track 5, is used for supporting the inner door 10, and extends over the doorway immediately below the track 5, and said track 18 projects longitudinally away from the doorway to that side opposite to the side toward which the track 5 projects. This track 10 18 embodies the trough-shaped portions 19 within which are mounted for rotation rollers 20 upon which the T-heads 17 of the hangers 16 seat, or said hangers 16 can be provided with a common T-head 17, so long 15 as said hangers can move freely along the track with the door 10. The slotted members 14 in slidably engaging the hangers 16 permit the door 10 to be moved outwardly to open it, and to be moved inwardly into the 20 door frame when said door 10 is closed.

The inner door 10 is provided adjacent its upper end with an opening 21 to enable the car to be readily filled with grain, by means of a chute, or the like. This opening 21 is 25 closed by an auxiliary door or gate 22 which is preferably hinged, as at 23, at its upper edge to the main door 10. This auxiliary door 22 can be hinged to swing either inward or outward, and can be held in closed 30 position in any suitable manner. The door 10 is also provided adjacent its lower end with a discharge opening 24 to permit the grain or other material to be discharged conveniently, whereby to start the emptying of 35 the car in a convenient and desirable manner. This opening 24 is normally closed, that is, when the car is filled, by means of an auxiliary door or gate 25 which is preferably hinged, as at 26, at its upper edge 40 to the door 10, whereby the door 25 can be swung outwardly. This door 25 can be held in closed position by means of any suitable latches or catches 27. The door 10 is provided upon its outer side with suitable 45 handles or hand holds 28 whereby said door can be moved or pulled outwardly conveniently.

The outer door 4 is offset inwardly relative to its hanger 9 so as to be disposed 50 under the track 18, and to be disposed closely adjacent to the outer surface of the frame. The hangers 16 are movable over the door 4 when said door is closed, and the upper edge of the door 4 and track 18 are 55 spaced apart to accommodate the members 14, as seen in Fig. 4.

As a means for holding the door 10 in 60 closed position against the stops 2^a of the jambs 2 at the inner sides thereof, vertical clamping plates or leaves 29 are mounted within vertical recesses 30 with which the adjacent sides of the jambs 2 are provided, and are secured upon vertical rock shafts or spindles 31 disposed within said recesses 65 and mounted for rotation within the jambs

2 above and below said recesses. The lower ends of the shafts 31 project through the sill 1, and have attached thereto handles or levers 32 by means of which the plates 29 can be readily swung into and out of the 70 recesses 30. When the plates 29 are re-tired within the recesses 30, the door 10 can be readily moved outwardly or inwardly, and when the door 10 is moved inwardly against the stops 2^a, the plates 29 can be 75 swung inwardly to clamp the edges of the door against said stops, thereby to hold the inner door firmly in place.

As a means for holding the plates 29 when swung into position to clamp the door 10 80 against the stops 2^a, rack bars 33 are slideable in slots 34 with which the jambs 2 are provided, and are projectible through the recesses 30 adjacent the outer sides of the plates 29, to hold said plates 29 against the 85 door 10, as seen in Fig. 2. These bars 33 are operated by pinions 35 secured upon shafts or spindles 36 journaled in the jambs 2 and projecting from the outer sides thereof. Handles or levers 37 are secured upon the 90 outer ends of the shafts 36 for rotating them. When the door 4 is moved out of the way, the handles 37 can be readily rotated for rotating the pinions 35 for either projecting or retracting the bars 33, but when the door 95 4 is closed, said handles 37 are concealed thereby, to prevent the inner door being released while the outer door is closed.

As auxiliary means for holding the door 10 in closed position, screws 38 can be 100 threaded upwardly through the sill 1 to threadedly take into apertures provided in the lower end of the door 10, or other suitable means can be used for holding the door 10 in closed position.

A longitudinal guide strip 39 is carried upon the exterior of the car body by brackets 40 and extends past the doorway adjacent the lower end thereof. This strip 39 prevents the doors 4 and 10 from being 110 swung outwardly away from the side wall of the car body, and assists in guiding said doors for longitudinal movement toward and away from the door way.

When the door 10 is closed, it fits within the 115 door frame against the stops 2^a, and is held firmly in place by the plates 29 which are in turn held in place by the rack bars 33 which have been projected by the rotation of the pinions 35. Now, when the door 4 120 is slid to closed position across the door way, it covers the handles 37, and prevents the inner door from being loosened. The inner door 10 provides a grain tight closure, which will also exclude the elements, and 125 which will successfully resist the pressure and jolts due to the jostling or wedging action of the merchandise. A person within the car cannot open the doors from the inside, since the outer door prevents the out- 130

ward movement of the inner door, and even though the inner door is loosened, it is impossible for a person within the car to get at the outer door to dislodge it.

To open the doors, the outer door 4, after the seal is broken, is moved longitudinally away from the door way to one side thereof, and the means which hold the inner door 10 are then released, permitting said inner door to move outwardly under the pressure of the contents of the car, and if the car is filled with grain, before the door 10 is released, the auxiliary door 25 can be opened to permit the discharge of grain in a convenient manner, whereby to start the emptying of the car. When the door 10 is released, it can be moved outwardly out of the door frame to the outer side thereof, as seen in Fig. 5, and said inner door 10 can then be moved longitudinally away from the door way in a direction opposite to that in which the door 4 is moved to open position, whereby one door will be at one side of the doorway and the other door at the opposite side. As above indicated, the guide strip 39 prevents the lower ends of the doors from swinging away from the car body. To close the door way, the doors 10 and 4 are moved to position in succession, as will be obvious from the foregoing.

Having thus described the invention, what is claimed as new is:

In a door structure, the door frame hav-

ing outwardly facing stops, a pair of tracks extending over the upper end of the doorway adjacent to one another at the outer side of the door frame and extending to opposite sides of said doorway, one track being disposed slightly below and spaced inwardly from the other track, a hanger 35 slidable along the second mentioned track and depending outside of the first mentioned track, an outer door hung from said hanger and offset inwardly under the first mentioned track to move along the outer 40 surface of said frame, a hanger slidable along the first mentioned track above said door, an inner door movable into the door frame against said stops, means for holding the inner door against said stops, the inner 45 door having outstanding members at its upper end slidably engaging the second mentioned hanger, the first mentioned door being immediately below the first mentioned track and second mentioned hanger when in 50 closed position, and said outstanding members being disposed between the first mentioned door and first mentioned track when the doors are in closed position.

In testimony that I claim the foregoing 60 as my own, I have hereto affixed my signature in the presence of two witnesses.

JOHN LAYTON GUERRANT.
